US0D1094741S

(12) **United States Design Patent** (10) **Patent No.:** **US D1,094,741 S**
(45) **Date of Patent:** **** Sep. 23, 2025**

(54) **NECK GASKET**

(71) Applicant: **John Richard Taylor**, Irving, TX (US)

(72) Inventor: **John Richard Taylor**, Irving, TX (US)

(**) Term: **15 Years**

(21) Appl. No.: **29/782,903**

(22) Filed: **May 10, 2021**

Related U.S. Application Data

(62) Division of application No. 29/697,810, filed on Jul. 11, 2019, now Pat. No. Des. 921,906.

(51) **LOC (15) Cl.** **24-01**

(52) **U.S. Cl.**

USPC **D24/201**

(57) **CLAIM**

The ornamental design for a neck gasket, as shown and described.

DESCRIPTION

FIGURE depicts an elevational view of a neck gasket. A top plan view, a bottom plan view, a left side view, and a right side view of this neck gasket are omitted because such views are non-claimed subject matter.

The broken lines showing portions of a wall illustrate environmental subject matter that forms no part of the claimed design.

1 Claim, 1 Drawing Sheet
